UNITED STATES PATENT OFFICE

111,862

DESIGN FOR A CASKET

Carl Schwendler, Winfield, Long Island, N. Y., assignor to National Casket Co. Inc., Long Island City, N. Y.

Application August 2, 1938, Serial No. 79,031

Term of patent 7 years

To all whom it may concern:

Be it known that I, Carl Schwendler, a citizen of the United States, residing at Winfield, Long Island, in the county of Queens and State of New York, have invented a new, original, and ornamental Design for a Casket, of which the following is a specification, reference being had to the accompanying drawings, forming part thereof, wherein—

Figure 1 is a top plan view;
Fig. 2 is a side elevation;
Fig. 3 is an end elevation; and
Fig. 4 is an enlarged fragmentary view of a corner of the casket, showing my new design.

I claim:

The ornamental design for a casket, substantially as shown.

CARL SCHWENDLER.
